(57) **CLAIM**

The ornamental design for a multipurpose magnet holder as shown and described.

DESCRIPTION

1. Multipurpose magnet holder

1.1 : Perspective

1.2 : Perspective

1.3 : Front

1.4 : Back

1.5 : Left

1.6 : Right

1.7 : Top

1.8 : Bottom

1.9 : Cross sectional

1.10 : Reference

1.11 : Reference

1.12 : Reference

The design is for a multipurpose magnet holder; a C-shaped elastic incision is formed on the front of the body to fix the connectors such as cables, HDMI terminals, electric plugs, and optical adapters by fitting and coupling, and two magnets are inserted into the grooves formed on the upper and lower parts on the back and magnetically coupled inside not to be fallen out; it can be used to easily fix the cables and connectors to desired location on electric reels, enclosures, walls, and electronic devices, etc. of steel structure; reproduction **1.1** (perspective view of the design), reproduction **1.2** (perspective view seen from the bottom of the design), reproduction **1.9** (cross-sectional view); reproduction **1.10** is a reference view of the state of use of combining cable and electric plug; and reproduction **1.11** is a reference view of the state of use of combining cable and HDMI terminal using this design; reproduction **1.12** is a reference view of the state of use of fixing the combined cable and HDMI terminal with this design by attaching them to the electric reel of steel structure; the parts shown by means of broken lines in the reproductions are not part of the claimed design.

1 Claim, 12 Drawing Sheets
